UNITED STATES PATENT OFFICE.

JOTHAM P. CARPENTER, OF ATTLEBOROUGH, MASSACHUSETTS.

DETACHABLE BUTTON.

SPECIFICATION forming part of Letters Patent No. 224,144, dated February 3, 1880.

Application filed September 26, 1879.

To all whom it may concern:

Be it known that I, JOTHAM P. CARPENTER, of Attleborough, county of Bristol, State of Massachusetts, have invented a new and useful Improvement in Detachable Buttons; and I hereby declare that the following is a full, clear, and exact description of the same, reference being had to the accompanying drawings, forming part of this specification.

10 This invention consists in the novel arrangement, with a pusher, of a spring contained in the shank of the button, and in the peculiar construction of the pusher, all of which will be more fully set forth hereinafter.

15 Figure 1 is a sectional view of the improved button, showing the shoe secured by the hooked end of the pusher and the spring contained within the tubular shank of the button. Fig. 2 is a view of the button-disk, showing the 20 pusher and the groove in which it slides. Fig. 3 is an enlarged view of the pusher, and Fig. 4 a view of the pusher-blank.

In the drawings, *a* is the button-disk. *b* is the tubular shank of the button. *C* is a groove 25 in which the pusher *d* slides. The end of the pusher *d* is bent over so as to form a hook, which extends over the projecting rim on the tubular shank *f* of the shoe. The spring *e* is pushed into the tubular shank *b*, one end entering the hole *g* in the pusher, and when the tubular shank *b* is secured to the disk *a* of the button the spring *e* is firmly retained, and yet free to act on the pusher *d*.

By placing the bent leaf-spring *e* into the tubular shank it is well protected against dust 35 or other impurities liable to interfere with the free working of the spring, and a neater and cheaper button is produced.

The pusher is stamped out of sheet metal, as shown in Fig. 4. The central portion, *h*, is 40 square, so as to slide in the groove *C*. The end *i* is turned over, as shown in Fig. 3, and the flat portion *K'* is drawn up in dies until the round end is formed.

This improved detachable button is simple 45 in construction, and all the parts are strong, durable, and the spring protected from injury.

Having thus described my invention, I claim as new and desire to secure by Letters Patent—

1. In a detachable button, the combination, with the button disk *a*, tubular shank *b*, and the shoe provided with the tubular shank *f*, having a projecting rim at its open end, of the pusher *d*, provided with the hook *i*, and the 55 spring *e*, placed within the shank *b*, arranged to operate substantially as and for the purpose set forth.

2. A pusher, *d*, provided with the square portion *h*, the bent hook *i*, the cylindrical portion *K'*, and the hole *g*, substantially as described.

JOTHAM P. CARPENTER.
